UNITED STATES PATENT OFFICE.

FRANK W. WALLACE, OF CHATTANOOGA, TENNESSEE, ASSIGNOR OF ONE-HALF TO
BLUCHER BLAIR, OF CHATTANOOGA, TENNESSEE.

ICE-HANDLING DEVICE.

Application filed October 28, 1926. Serial No. 144,760.

In removing ice cubes from the pans of household electric refrigerators, it is customary to invert the pan of ice upon one hand and run water over the bottom of the pan to loosen the ice, permitting removal of the pan with one hand while the ice remains deposited upon the other hand. This procedure is objectionable to a great many people because of the severe chilling effect which the ice has upon the hands. Moreover, when a servant performs this duty, her hand must come in contact with all cubes of the ice, which for sanitary reasons is quite often objectionable.

It is the object of my invention to provide a novel form of tray into which the ice cubes may be discharged from the pan, so that the ice need not touch the hand, thereby overcoming the difficulties above pointed out, said tray being of such form that while it will effectively retain the ice cubes, they may be slid readily from its front end, for use.

With the foregoing in view, the invention resides in the novel subject matter herein-after described and claimed, the description being supplemented by the accompanying drawing.

Fig. 1 is a perspective view showing the manner of using the device.

Fig. 2 is a perspective view of the form of tray shown in Fig. 1.

Fig. 3 is a plan view partly broken away and in section, showing a slightly different form of tray.

Fig. 4 is a side elevation of the tray shown in Fig. 3.

The numeral 5 on the drawing, designates a tray constructed in accordance with my invention, said tray comprising a bottom 6, side walls 7 rising therefrom, and a back wall 8 also rising from the bottom and secured to the rear ends of the side walls. The front end of the tray is not provided with an upstanding wall, in order that the ice cubes may readily be slid forwardly therefrom. Preferably, the rear end of the tray is provided with means to permit drainage of water therefrom. In Fig. 2, a number of sawcuts 9 are shown for this pur-

pose, while in Figs. 3 and 4, openings 10 are formed in the bottom 7, and the rear lower corners of the side walls 7 are cut away as at 11. With regard to the drainage means, the drawings are only illustrative of two of the many provisions which could be made for this purpose.

The tray 5 is of substantially the same size as one of the ice pans P of a household electric refrigerator, and in using this tray, it is held in one hand while a pan of the ice cubes is inverted upon it with the other hand, as shown in Fig. 1. Then, water may be run over the inverted pan to loosen the ice, causing the latter to drop into the tray. In this tray, the ice cubes may be carried to the point at which they are to be used, and the cubes may be slid one at a time or simultaneously from the open front end of the tray, as occasion may demand.

The device may be formed from wood if desired, or any other adequate material may be employed. Such material however, is preferably more or less of an insulator against cold, to prevent noticeable chilling of the hand in which the ice laden tray is held.

I claim:

A device for handling ice from a household electric refrigerator of the type provided with a pan in which the ice is frozen in cubes; said device comprising a tray made of non-metallic material and upon which to invert the pan of ice with one hand while holding said tray with the other hand, whereby upon loosening of the ice from the pan it will be deposited in the tray, said tray having an imperforate rectangular bottom and imperforate back and side walls of a height corresponding to an ice cube, said back wall and the rear portions of the side walls being formed with saw cuts which extend into the bottom to provide drain openings, the front end of the tray being open to permit the ice cubes to slide from this end of the tray.

In testimony whereof I have hereunto affixed my signature.

FRANK W. WALLACE.
